Attorney

UNITED STATES PATENT OFFICE.

BERT E. HILBORN, OF SPOKANE, WASHINGTON.

CLAMP.

1,389,587.

Specification of Letters Patent. Patented Sept. 6, 1921.

Application filed November 9, 1920. Serial No. 422,925.

To all whom it may concern:

Be it known that I, BERT E. HILBORN, a citizen of the United States, and resident of Spokane, in the county of Spokane and State of Washington, have invented certain new and useful Improvements in Clamps, of which the following is a specification.

My invention relates to a device for holding cards, posters, signs and various other similar advertising and display matter in proper position upon supporting surfaces, and its object primarily is to eliminate the use of tacks, paste, stickers and other forms of retainers heretofore employed for this purpose.

The device of my invention consists of a clamp, any number of which are adapted to be permanently secured to a support such as a bill board, a wall, the side of a vehicle or other surface, in any desired relation, for releasably holding the edges of a card, poster, sign or the like, whereby the same is held in position for display and whereby substitution of one card or sign for another may be quickly effected with little effort and at minimum cost.

Furthermore, it is a purpose of my invention to provide a clamp for the purpose mentioned which will operate to hold a card, poster or sign directly in contact with a supporting surface so that the same will remain perfectly smooth and not liable to become torn during the period it is displayed.

My inventive idea is capable of embodiment in different mechanical structures, one of which is illustrated in the accompanying drawings, but it is to be understood that the structure shown is merely intended to disclose the essential features of my invention in a preferred form and that its scope is as defined in the appended claims.

In the drawings, wherein like characters of reference denote corresponding parts in the different views:—

45 Fig. 1 is a view in front elevation showing the manner of holding a card, poster or the like by my improved clamp;

Fig. 2, an enlarged edge view of one of my clamps; and

50 Fig. 3, a perspective showing the parts of my clamp in separated relation.

Referring to the drawings in detail, 10 designates the base of my clamp which is preferably formed from rigid sheet metal and includes apertured ears 11 conveniently disposed thereon to receive screws, bolts or

other devices for permanently fastening the same to a sign board, wall or other support. Projecting perpendicularly outward from the base is a threaded stud 12 and adjacent this stud a portion of the base is bowed outwardly as at 13.

A rigid sheet metal plate 14 of substantially rectangular elongated shape has a portion 15 thereof, near one end, bowed outwardly, and at its other end has an inturned flange 16. The bowed portion 15 terminates in a reversely curved lip 17, and an opening 18 is formed in the plate through which the stud 12 freely passes when the base 10 and this plate are in assembled relation, in which position a wing nut 19 is threaded on the stud whereby the plate 14 may be forced into clamping relation with the base plate.

By particular reference to Fig. 2 of the drawings, which shows the relative clamping position of the plates, it will be observed that the inturned flange 16 coöperates with an edge of the base plate to prevent relative twisting or turning movement of the plates, and it will also be observed that the bowed portion 15 overlies the bowed portion 13 and that the lip 17 extends slightly beyond the adjacent edge of the base plate as well as somewhat inwardly of the outer face of the latter.

When the plates are in assembled relation with the wing nut 19 threaded on the stud, the outer end of the latter is preferably burried over to prevent removal of the nut 90 and consequently eliminates the possibility of parts of the clamp becoming lost. Burring of the end of the stud, however, will in no way effect the operation of the device.

With a preferred number of my devices 95 secured in desired relation to a support, a card, poster, sign or the like, such as designated at A in the drawings, irrespective of its size or shape, may be quickly secured in position for display thereby and as quickly 100 released to permit another card, poster or sign to be substituted in its stead. To secure the rectangular card A I preferably employ four clamps, one adjacent each corner of the card, and between the plates 10 and 14 of 105 each clamp I insert an edge of the card so that it will lie between the bowed portions 13 and 15, after which I turn the nut 19 to clamp the edges of the card between adjacent faces of said bowed portion. When 110 secured by the clamps the card is maintained in position flat against the surface upon

which the base plates 10 are mounted by the lips 17 as plainly shown in Fig. 2.

I claim:

1. A device of the character described comprising a base plate adapted to be permanently secured to a support, a clamp plate, means to force said plates together to clamp a portion of an article therebetween, and means on one of said plates to hold the article clamped between the plates in flat contact with the surface of said support.

2. A device of the character described comprising a base plate having a bowed portion, a clamp plate having a bowed portion overlying said first bowed portion, said clamp plate including a lip adjacent to the bowed portion thereof and reversely curved with respect thereto, and means for forcing said plates together whereby a portion of an article is held in contact with a surface by said lip.

3. A device of the character described comprising a base plate adapted to be secured to a support, a clamp plate, means to force said plates together to clamp an article therebetween, and a lip on said clamp plate the terminal of which acts to hold the article clamped between said plates in contact with said support.

4. A device of the character described comprising a base plate adapted to be secured to a support, a clamp plate, means to force said plates together to clamp an article therebetween, and a lip on said clamp plate extending inwardly beyond the outer face of the base plate when said plates are clamped together whereby the article clamped between said plates is maintained in flat contact with said support.

In testimony whereof I hereunto affix my signature.

BERT E. HILBORN.
